Inventor:

William Alfred Lundell

UNITED STATES PATENT OFFICE

2,239,239

TWO-CYCLE ENGINE CARBURETION
SYSTEM

William Alfred Lundell, Tacoma, Wash.

Application February 27, 1940, Serial No. 321,051

3 Claims. (Cl. 123—73)

My invention relates to improvements in two-cycle engine carburetion system, and the objects of my improvements are: first, to eliminate the fuel leakage around the pistons and out of the exhaust ports; second, to more thoroughly atomize the fuel in its very short travel into the combustion chamber, thereby saving fuel; third, to eliminate carburetion icing trouble in aviation use; fourth, to cause higher volumetric efficiency; fifth, to cause a very easy starting motor. I attain these objects by the mechanism illustrated in the accompanying drawing in which:

Fig. 1 is a vertical section of the structure as attached to a single-cylinder, two-cycle motor.

Fig. 2 is a side view of rocker arm and rocker-arm return spring.

Fig. 3 is an inside view of the structure.

Similar numerals refer to similar parts throughout the several views.

The structure 7 embodies the manually operated raw-fuel varying valve lever 8 and needle 6, which has its seat on the raw-fuel jet 17. It also embodies the raw-fuel jet 17 opening and closing disc 18, which is rocked by the shaft 11 and the shaft end 3. The shaft 11 is rocked by the action of the cam 15 on the crank shaft 14 through tappet 13, push rod 12, and rocker 9. Fuel pipe 5 supplies raw-fuel to jet 17.

The action of this system is as follows: The piston 2, in its travel on its up stroke, creates a vacuum in the crank case 16, which, having a communicating passage through ports 4 and piston ports 22, creates a vacuum in the chamber 23. While the piston 2 is traveling up on its up stroke, the crank shaft 14 has turned cam 15 so as to lift tappet 13 and the push rod 12; and it also has rocker 9, which in turn, has turned shaft 11 through a short arc as in Fig. 3 (from 18 dotted to 18) thereby opening the raw-fuel jet 17. As there is a vacuum in this chamber 23 (previously created), a raw-fuel charge is drawn into chamber 23. Now, as the piston 2 starts on its down stroke, the crank 14 has turned the cam 15 so that the tappet 13, push rod 12, and rocker 9 have returned to their lowered positions by the action of the spring 10. The above action rocks shaft 11, end 3, and jet 17, cover disc 18, back over the jet 17 into closed position shown as 18 dotted. As the piston 2 continues on its down stroke, pure air pressure is built up in the crank case 16 until piston 2 uncovers exhaust port 19. The exhaust port

19 having cleared the cylinder of burnt gases and the further travel of piston 2 on its downward stroke uncovers by-pass ports 4. At the same time piston ports 22 line up with ports 4, thereby by creating a free passage for the pure air from crank case 16 into combustion chamber 24. Now as pure air, in its rush up into chamber 24, travels at a high velocity, thereby picking up the raw-fuel charge (that was drawn into the by-pass 23 previously on the up stroke of piston 2) and atomizing the raw fuel by the blast of air on its travel into the combustion chamber 24.

Pure air is drawn into the crank case 16 by the piston 2, creating a vacuum in the crank case 16 on said piston's up-stroke until it uncovers and opens the air intake ports 20 wide open. Then air rushes in until piston 2 on its down stroke covers ports 20 locking the air in crank case 16. It should be noted that there is no carburetor nor any other obstruction covering the ports 20, thereby increasing the volumetric efficiency of the engine.

I do not wish to be limited to the precise details of construction as shown, as changes in construction can be made without departing from the principle of my invention.

I claim:

1. In an internal combustion engine, the combination of a cylinder and a crankcase, a bypass connecting the cylinder and crankcase for the passage of scavenging air from the crankcase to the cylinder, a liquid fuel jet opening into said bypass, a valve seat for said fuel jet, a sliding disc on said valve seat and means for operating said sliding disc so that the liquid fuel is injected into the air as it passes from the crankcase to the cylinder.

2. The combination, in a two-cycle engine mechanically operated by-pass structure raw fuel metering valve, a sliding raw fuel cut off or metering disc, a sliding raw fuel metering disc seat, mechanical means for operating the raw fuel cut off disc, a raw fuel jet, means for manually controlling fuel to the raw fuel jet.

3. The combination in a two-cycle engine bypass structure mechanically operated raw fuel metering jet, a raw fuel metering disc, a raw fuel metering disc seat, mechanical means to operate the raw fuel metering disc from engine crank shaft, a raw fuel jet, a manually operated raw fuel jet, fuel control valve.

WILLIAM A. LUNDELL.
